UNITED STATES PATENT OFFICE.

EARLE B. STOUT, OF GARY, INDIANA.

GAME APPARATUS.

Application filed February 10, 1925. Serial No. 8,248.

To all whom it may concern:

Be it known that I, EARLE B. STOUT, a citizen of the United States, residing at Gary, in the county of Lake and State of

5 Indiana, have invented certain new and useful Improvements in Game Apparatus; and I hereby declare that the following is a full, clear, and exact description thereof, reference being had to the accompanying 10 drawings, which form part of this specification.

This invention is a novel game or educational appliance, and the principal object of the same is to construct what I term 15 "magic cubes" consisting of a group of consecutively numbered blocks arranged to form a large cube in such manner that the numbers appearing on the blocks in each row which are disposed parallel with any 20 of the side edges of the "magic cube," and most, if not all, of the diagonals have the same total sum.

A further object of the invention is to construct such "magic cubes" by the use 25 of a building set comprising construction cards, game cards, blocks, and chips, as hereinafter described having predetermined arrangements of letters, figures, or groups of figures upon one or more or all of their 30 faces, the game being educational as well as amusing and entertaining; each block, moreover, having a "magic square" on one face so that a person having an inquiring disposition will study these 35 "magic squares" to find out how they are constructed, and such study will prove educational. Chance is eliminated from my game, and strict compliance with instructions will enable any one to build a "magic 40 cube".

I will explain the invention with reference to the accompanying drawings which illustrate my building set to enable others to adopt and use my invention, and will 45 summarize in the claims the essentials of the invention, the novel features of construction, and novel combinations of parts, for all of which protection is desired.

In said drawings:

50 Figure 1 is a plan view of one of the "magic cube cards".

Figure 2 is a plan view of the slide used with the card shown in Figure 1.

55 Figure 3 is a plan view of one of the "temporary cube cards".

Figure 4 is a view of the "row series"

slide used with the card shown in Figure 3. Figure 5 is a view of the "column series" slide used with the card shown in Figure 3.

60 Figure 6 is a section on the line 6-6, Figure 1.

Figure 7 is a section on the line 7-7, Figure 3.

Figures 8 and 9 are perspective views of 65 one unit cube or block.

Figure 10 is a view of one "letter key chip".

Figure 11 is a view of one "figure key chip".

70 Figure 12 is a view of one "attendant key-square".

Figure 13 is a view of one of the "letters".

Figure 14 is a view of one of the "attendants".

Figure 15 is a view of one of the "figures".

Figure 16 is a view of one of the game 80 boards.

Figure 17 shows a 64 block "magic cube" constructed by my invention.

Figure 18 shows the horizontal layers of the cube shown in Figure 17 slightly separated.

85 As shown in the drawings, my preferred form of "magic cube" building set comprises sixty-four consecutively numbered blocks 1 (Figures 8 and 9); eight construction cards 2 and 3 (Figures 1-7); sixteen lettered chips or "letters" 4 (Figure 13); sixteen numbered chips or "figures" 5 (Figure 15); sixty-four numbered chips or "attendants" 6 (Figure 14); twenty "attendants key-squares" 7 (Figure 12); sixteen "letter key chips" 8 (Figure 10); twenty "figure key chips" 9 (Figure 11); four game boards 10 (Figure 16); and a book of instructions (not shown).

95 The sixty-four blocks 1, shown in Figures 8 and 9, may be made of any suitable material, such as wood, card board, celluloid, or the like the blocks being numbered, as at 1^a, consecutively from one to sixty-four, the number 1^a preferably appearing 100 on five of the six faces of each block. On one of the five numbered faces of each block the words "Magic blocks" may appear. (Figure 8). On the sixth face of each block appears what I term a "magic 105 square" consisting of certain predetermined numbers arranged in as many parallel

rows as there are numbers in each row, the sum of each of the rows of numbers, either vertical or horizontal, and one if not both of the main diagonals, being the same. The words "magic square" may appear on said face, and the sum total of the respective rows, as shown in Figure 9. A person having an inquiring disposition may study the "magic squares" appearing on the blocks 10 1, to find out how the same are constructed, and such study will prove educational. Instead of the "magic squares" 1^b, on some of the blocks construction plans (not shown) for particular "magic squares or 15 cubes" may be given.

The eight construction cards 2 and 3, as shown, comprise two sets of four cards each, the sets being somewhat different, the cards 2 (Figure 3) being what I term "temporary cube cards", and the cards 3 (Figure 1) being what I term "magic cube cards". Upon each card 2 and 3 are sixteen squares 2^a, 3^a, respectively arranged in four parallel rows of four squares each.

The sixteen squares 2^a of the "temporary cube cards" 2 are marked as at 2^x "Temporary sq. #1," and so on to #16 respectively, as shown in Figure 2, reading from left to right, beginning with the top row. Opposite each horizontal row of squares 2^a is an opening 2^b marked "Row," and near the bottom of card 2, and in alignment with the openings 2^b is an opening 2^c, marked "Row series." A slide 2^d (Figure 4) is vertically movably mounted behind the openings 2^b, 2^c, said slide bearing as at 2^e the letters "A," "B," "C," and "D" adapted to be displayed through the opening 2^c as slide 2^d is shifted, and also bearing four groups 2^f of numbers 1, 2, 3, or 4, one number of each group adapted to be displayed through its respective opening 2^b simultaneously with the registering of a letter "A," "B," "C" or "D" 40 with opening 2^c, the particular order or arrangement of the numbers of each group 2^f with respect to letters 2^e, being predetermined and fixed.

Below each of the vertical rows of squares 50 2^a of cards 2, is an opening 2^g marked "Column" and in alignment with the openings 2^g is an opening 2^h marked "Column series." A slide 2^k is vertically movably mounted behind openings 2^g, 2^h, said slide 55 2^k bearing, as at 2^m, the letters "A" to "I" inclusive, adapted to be successively displayed through openings 2^h as slide 2^k is shifted; also four groups 2ⁿ of numbers ranging between 1 and 16 inclusive, one 60 number in each group 2ⁿ being adapted to be displayed through its respective "column" opening 2^g simultaneously with the registering of a letter "A" to "I" with opening 2^h, the particular order or arrangement 65 of the numbers of each group 2ⁿ with re-

spect to the letters 2^m being predetermined and fixed.

In each of the squares 3^a of the magic cube cards is an opening 3^b marked "Square number" and near the bottom edge of each 70 card 3 is an opening 3^c marked "Square series." A slide 3^d (Figure 2) is vertically movably mounted behind openings 3^b, 3^c, said slide bearing a row 3^e of letters "A" to "I" inclusive, adapted to be displayed 75 through opening 3^c as the slide is shifted in the card 3; and also groups of numbers 3^f, ranging 1-16 inclusive, one number of each group 3^f being adapted to be displayed 80 through its respective opening 3^b in the card 3 simultaneously with the registering of a letter with openings 3^c, the particular order and arrangement of the numbers of each group 3^f being predetermined and fixed.

The four "temporary cube cards" 2, the four "magic cube cards" 3; and their respective slides 2^d, 2^k and 3^d, are marked "Layer #1," "Layer #2," "Layer #3," and "Layer #4," respectively, as shown in Figures 1-5 inclusive.

For each setting of the slides 2^k of any of the cards to the "column series" A, B, C, etc. (displayed through openings 2^h) the sum of all the numbers appearing through 95 openings 2^g on each card will equal a constant number (34). Also for each setting of the slides 3^d of any of the cards 3 to the "square series" A, B, C, etc. the sum total of the numbers appearing through each of the horizontal and vertical rows of openings 3^b of each card 3 will equal a constant number (34).

The sixteen lettered chips or "letters" 4, as shown in Figure 13, comprise four groups 105 of four chips each, the chips of each group bearing the indicia "Letter A," "Letter B," "Letter C," and "Letter D," respectively. The sixteen numbered chips or "figures" 5, as shown in Figure 15, bear the 110 indicia "Figure" and are numbered 1-16 consecutively. The sixty-four "attendants" 6 as shown in Figure 14, comprise four groups of sixteen chips each, the chips of each group being marked "Queen's attendant #1" and so on to "#16." The twenty 115 "attendant key squares" 7 as shown in Figure 12, comprise five groups of four chips each, the chips of each group being identical, and each group bearing the numbers 120 1-16 inclusive, arranged in four rows of four numbers each, so that each horizontal and vertical row of numbers has a sum total of 34. Each group however has a different arrangement of the numbers.

The sixteen "letter key chips" 8 shown in Figure 10, comprise four groups of four chips each, the chips of each group being identical, and each chip bearing four different combinations of the letters "A," "B," 130

"C" and "D," the different combinations being marked "First layer," "Second layer," "Third layer," and "Fourth layer" respectively. The combinations for the layers of each group are however different from those of the three other groups.

The twenty "figure key chips" 9 shown in Figure 11, comprise 5 sets of four chips each, the chips of each set being identical, and each chip bearing the numbers 1-16 inclusive arranged in four groups of four numbers each so that the sum total of each group on each chip is 34, the four groups of each chip being marked "First layer," "Second layer," "Third layer" and "Fourth layer" respectively. The combinations of numbers for the corresponding layers of each set are different.

The four game boards 10, shown in Figure 16, are identical except as hereinafter set forth. At the left hand side of each board 10 is a square 10^a comprising four rows of four spaces each. At the top of square 10^a are the words "Temporary cube", and at the left hand side of square 10^a are circles 10^b, opposite each horizontal row of spaces in square 10^a, the circles 10^b being marked "Letters." At the bottom of square 10^a are circles 10^c opposite each of the vertical rows of spaces of the square 10^a, said circles 10^c being marked "Figures." At the right hand side of each board 10 is a square 10^d, of same size, and similar to square 10^a, but each space in square 10^d has inscribed therein a circle 10^e. At the top of square 10^d are the words "Magic cube," and at the bottom of square 10^d the word "Attendants." The four game boards are marked "First layer," "Second layer," "Third layer," and "Fourth layer" respectively.

There are two methods of constructing "magic cubes" as shown in Figures 17 and 18, with the above building set, the two methods being based upon the same principle.

The first method, or construction card method, provides a form of "solitaire" to be played by one person only, the object being to construct the "magic cubes" rapidly, and to study the many possible combinations or cubes obtainable. This method makes use of the sixty-four numbered blocks 1, and the eight construction cards, i. e., the four "temporary cube cards" 2, and the four "magic cube cards" 3. The construction cards should be disposed in two rows, with the "temporary cube cards" 2 in one row, and the "magic cube cards" 3 in the other row, the layers 1, 2, 3, 4 in each row reading from left to right. Then set the slides 2^a, 2^b and 3^a of the cards 2 and 3 so that any of the letters "A," "B," "C," etc., are displayed through their respective openings 2^c, 2^d and 3^c, duplicating their ar-

angement on each layer and place the blocks 1, in numerical order, (1, 2, 3, etc.) on the squares 2^a of the temporary cube cards 2, as follows:

Block #1 on the square in row #1, 70 column #1; block #2 on the square in row #2, column #1; block #3 on the square in row #3, column #1; block #4 on the square in row #4, column #1; block #5 on the square in row #1, column #2; block #6 on the square in row #2, column #2; block #7 on the square in row #4, column #2; block #8 on the square in row #1, column #3; block #9 on the square in row #2, column #3; block #10 on the square in row #4, column #3; block #11 on the square in row #1, column #4; block #12 on the square in row #2, column #4; block #13 on the square in row #3, column #4; block #14 on the square in row #4, column #4.

There is now a block 1 on each of the sixty-four squares 2^a of the four temporary cube cards 2. The blocks 1 thus arranged must then be transferred from the squares 2^a of each layer of the temporary cube cards 2 to the squares 3^a of each corresponding layer of the "magic cube cards" 3 as follows:

Place the block from "temp. sq. #1" on magic sq. #1; place the block from "temp. sq. #2" on magic sq. #2; place the block from "temp. sq. #3" on magic sq. #3; place the block from "temp. sq. #16" on magic sq. #16.

Then complete the "magic cube" by placing the layers, as thus arranged on the magic cube cards, on top of each other, layer #3 being placed upon layer #4; layer #2 upon layer #3; and layer #1 upon layer #2. By examining the cube thus constructed it will be seen that the sum total of each of the horizontal and vertical rows of numbers on each face of the cube, and most if not all of the diagonals equals a constant number. Since there are provided in the set above described four "row series" changes, nine "column series" changes, and nine "square series" changes, there will be $4 \times 9 \times 9 = 324$ different "magic cubes" which can be constructed with the above described set, by simply varying the combinations of the series changes, by setting the slides 2^a, 2^b and 3^a.

Referring to Figures 17 and 18, which show one of the 324 different cubes constructed by the above described set, the sums of the respective horizontal and vertical rows of blocks in the layers of the cube as well as in the complete cube, equals a constant figure 130.

The second method, or game method, is designed primarily for a plurality of players, from one to five, and offers awards and penalties for speed and accuracy. All the equipment is used, with the exception of the eight construction cards, 2 and 3. If more than one person is playing the four game boards 10 should be divided among the players, one player being selected to deal out the equipment.

The game proceeds as follows: The dealer will first decide which of the groups of letter key chips 8 will be used, and (as-

suming there are four players) will deal each player a chip 8 of said group; also four letters A, B, C, and D (Figure 13) which the players will arrange on their respective game boards 10 in the "letter" circles 10^a, using the arrangement shown on the key chip 8 for their respective layers, starting at the top circle 10^a and working down.

10 The dealer should next decide upon the particular group of "figure key clips" 9 to be used, and will then distribute the sixteen numbered chips or "figures" 5 to be placed by the players upon the "figure" 15 circles 10^a of their respective game boards 10, in the exact arrangement for their respective layers, as indicated on the key chips 9.

10 The dealer will then decide upon the 20 particular group of attendant key squares 7 to be used, and will deal to each player a key-square 7 of said group, together with a set of 16 "attendants" 6 (numbered 1-16 inclusive). The players must arrange the 25 attendants 6 on the spaces in squares 10^a of the "magic cube" half of the boards 10 in the exact order given on the key squares.

10 The game boards 10 being thus properly "set", the dealer will then deal the blocks 30 1, in numerical order and four at a time, to the players. The first group of four blocks should be dealt to the player on whose board the figure chip #1 is located. The second group of four blocks should be dealt 35 to the player on whose board the figure chip #2 is located, and so on until the sixteen groups have been distributed. The players must be observant as to when their turn to demand a group of blocks arrives, for if 40 they receive blocks out of their proper turn their respective layers will not become magic, and they will be subject to penalty.

10 The dealer will call for figure 1 and the player at the board where figure 1 is located must promptly indicate that he is to receive the first four blocks by answering. Upon receipt of the blocks the player will distribute them in the column marked "Figure 1," placing the first block in the 50 square governed by "letter A"; the second block in the square governed by "letter B"; the third block in the square governed by "letter C;" the fourth block in the square governed by "letter D." After the dealer 55 has given the first four blocks to the player having figure 1, he will call for figure 2, and the player at the board where figure 2 is located will receive his blocks, and distribute them in the column marked Figure 60 2, as explained above. The dealer continues to call for the figures until all of the sixty-four blocks have been dealt.

10 The dealer should then give a signal and each player should transfer the blocks from his "temporary cube squares" 10^a to his

"magic cube squares" 10^a in the following manner:—Beginning at the upper left hand space of the temporary cube square 10^a and in the order of row by row (i. e. line by line) the player takes a block at a time and places 70 it on the spaces in the magic cube square 10^a in the order indicated by the "attendants" 6. Thus the first block enters the square governed by attendant 1; the second block enters square governed by attendant 75 2; the third block enters square governed by attendant 3, etc., to 16th block which enters square governed by attendant 16.

10 The player completing first may receive a reward of 100 points for speed. The 80 player finishing second may receive 50 points for speed. The player finishing third may receive 25 points for speed.

10 Each player should then check up on his board and may receive the following 85 points for accuracy, and the following penalties for inaccuracy. For each column whose sum equals 130—10 points reward. For each row whose sum equals 130—10 90 points reward. For each diagonal whose sum equals 130—10 points reward. For each squarelet (four adjacent numbers) whose sum equals 130—20 points reward. For each column whose sum is not 130—10 95 points penalty. For each row whose sum is not 130—10 points penalty. For each diagonal whose sum is not 130—5 points penalty. For each squarelet whose sum is not 130—5 points penalty.

10 After each board has been checked and 100 points awarded to the players, the player having the highest score will form the "magic cube" by placing the blocks of the third layer on top of the blocks of the fourth layer; the second layer on the top 105 of the third layer; and the first layer on top of the second layer, being careful not to disturb the positions of the blocks in each layer.

10 For each additional and different diagonal, column, row or squarelet of four numbers, which he can find by examination of the completed cube, ten points may be added 110 to his score.

10 This completes the first quarter of the 115 game. New dealers should be chosen for the remaining three quarters of the game, choosing new sets of figure, letter and attendant key chips, and the game will proceed as given above. If there is a tie at 120 the end of the fourth quarter of the game, another cube will be built to determine the winner. The player having the largest number of points at the end of the fourth quarter wins the game.

10 While I have described the set as adaptable to a sixty-four block cube, the set could obviously be adapted for a 27 or 125 block cube, or even higher cubes within the scope of the invention.

I do not limit my invention to the exact form shown in the drawing for obviously the different parts could be modified within the scope of the invention.

5. I claim:

1. In a game apparatus having a plurality of consecutively numbered blocks adapted to be arranged in a plurality of vertical and horizontal layers to form a cube; a construction card having divisions thereon corresponding in number with the number of blocks in a layer of said cube; said card having indicia in each division, and having a vertical row of openings opposite each horizontal row of divisions, and having a horizontal row of openings opposite each vertical row of divisions; a slide movably mounted behind the vertical row of openings; and a slide movably mounted behind the horizontal row of openings; each slide bearing indicia thereon adapted to be displayed through its related openings.
2. In a game apparatus having a plurality of consecutively numbered blocks adapted to be arranged in a plurality of vertical and horizontal layers to form a cube; a game board having two squares thereon, and each square having divisions therein corresponding with the number of blocks in a layer of said cube; a set of consecutively lettered chips for the board adapted to be placed adjacent one of the squares with one chip opposite each horizontal row of divisions of said square; a set of consecutively numbered chips for the board adapted to be placed adjacent the same said square with one chip opposite each vertical row of divisions of such square; a letter key chip for the board; a figure key chip for the board; a second set of consecutively numbered chips for the board; and a key-square chip for the board.
3. A game apparatus comprising a plurality of consecutively numbered blocks adapted to be arranged to form a cube hav-

ing a plurality of layers; a game board for each layer of blocks in the cube, each board having two squares thereon each square having divisions therein corresponding with the number of blocks in a layer of said cube; a set of consecutively lettered chips for each board adapted to be placed adjacent one of the squares with one chip opposite each horizontal row of divisions of said square; a set of consecutively numbered chips for each board adapted to be placed adjacent the same said square with one chip opposite each vertical row of divisions of such square; a letter key chip for each board; a figure key chip for each board; a second set of consecutively numbered chips for each board; and a key-square chip for each board.

4. In a game apparatus as set forth in claim 3, each letter key chip having a plurality of sets of letters arranged in different groups to accord with the layers of blocks in the cube to be constructed, and each group referring to its particular layer of the cube.

5. In a game apparatus as set forth in claim 3, each figure key chip bearing as many numbers as there are blocks in a layer of the cube, said numbers being divided into groups corresponding in number with the number of layers in said cube; the sum of the numbers in each group equalling the same total, and each group referring to its particular layer of the cube.

6. In game apparatus as set forth in claim 3, each key-square chip bearing as many numbers as there are blocks in each layer of the cube the numbers being arranged in vertical and horizontal rows; the sum of the numbers in each horizontal, vertical and diagonal row on said chip being equal.

In testimony that I claim the foregoing as my own, I affix my signature.

EARLE B. STOUT.
